MIXER CIRCUIT ARRANGEMENT

Lester L. Libby, East Orange, N. J., assignor to
 Federal Telephone and Radio Corporation, New
 York, N. Y., a corporation of Delaware

Application December 27, 1944, Serial No. 569,964

4 Claims. (Cl. 250—20)

1

This invention relates to mixer circuit arrangements particularly of the type used for frequency conversion.

In certain conventional frequency-converting arrangements employing a mixer tube, such as those found in superheterodyne receivers, the received or incoming high frequency energy is combined with high frequency energy from a local oscillator to produce lower or intermediate frequency energy. In such receivers, the tuning of the input circuits of the receiver and the tank circuit of the oscillator are correspondingly varied so that the resultant intermediate frequency output of the mixer circuit is always a constant frequency.

Receivers of the type hereinbefore indicated may be designed to cover one or more relatively wide bands. In such receivers, it has been found that the lower frequencies of each band are discriminated against. This is in part due to the less favorable L/C ratio of the tuning circuits of both the receiver and local oscillator at the lower ends of each band than at the upper ends of each band. This fault is further accentuated at the higher bands when two or more bands are employed and changeover from a lower band to the higher bands is accomplished by switching the inductance coils employed while utilizing the same condenser arrangement. In the higher bands, the L/C ratio becomes more unfavorable and the discrimination at the lower end of the higher bands relative to the upper end of each of said higher bands becomes even more marked.

An object of the present invention is the provision of a frequency conversion arrangement which will not discriminate against the lower frequencies of each band covered by said arrangement.

Said low frequency discrimination in such arrangements is to a great extent caused by the oscillator which injects into the mixer circuit lesser voltages at the lower frequencies of each band than at the upper frequencies thereof.

Another object of the present invention is the provision of a local oscillator and arrangement for injecting voltages into a mixer circuit which will not discriminate against the lower frequencies.

Since, however, the input tuning circuits of the receiver will of themselves discriminate to some extent against the lower frequencies, it will be seen that despite the injection of equal voltages by the oscillator over all the frequencies of a given band, the output of the mixer circuit will still show some low frequency discrimination.

2

A further object of the present invention is the provision of a local oscillator and arrangement for injecting voltages into a mixer circuit which will favor the lower frequencies. Thus, by favoring the lower frequencies in the oscillator and its injecting arrangement, the tendency to discriminate against the lower frequencies in the input circuits feeding into the mixer is balanced and a substantially flat output is derived from the mixer over all the frequencies of each band.

Other objects of the present invention will become apparent and the foregoing will be best understood from the following description of an embodiment thereof, reference being had to the drawing, in which:

Fig. 1 is a schematic diagram of a circuit embodying my invention; and

Fig. 2 is a set of curves to which reference is made hereinafter, said curves not being intended to have any exact quantitative significance but merely serving as an aid in describing my invention.

Describing generally the mixer circuit arrangement of Fig. 1, potential from an alternating current source 1, which may be an antenna or a radio frequency amplifier or the like, is applied through any suitable coupling means such as a coupling condenser 2 to the input circuit 3 of a mixer generally designated by the numeral 4. In the mixer 4, energy from the source 1 is mixed with energy from a local oscillator generally designated by the numeral 5. The entire arrangement is adapted to operate over a plurality of bands of frequencies and means are provided for correspondingly tuning both the input circuit 3 and the oscillator 5 with the oscillator tracking the input circuit. The resultant output of the mixer is an intermediate frequency.

Since there is a tendency on the part of the mixer, any previous radio frequency stages, and the oscillator to discriminate against the lower frequencies of each band, in accordance with my invention means are provided for counter-balancing this tendency. Said means comprises a tuned circuit 6 which couples the oscillator to the mixer and which circuit is tuned at the lower end of the band of frequencies of the oscillator output. As will be explained hereinafter, this causes the potentials applied to the mixer from the oscillator to be of greater amplitude at the lower end of each frequency band than at the upper end thereof.

Describing now in detail the arrangement of Fig. 1, the input circuit 3 of the mixer 4 includes a tuning condenser 7 and a pair of coils 8 and 9

across one of which the condenser 7 is connected by means of a switch arm 10 of a multiple switch arrangement 11, coil 8 being connected for the lower frequency band and coil 9 for the higher frequency band. One end 12 of the input circuit 3 is connected to the control element or grid 13 of an electron discharge device or tetrode 14 while the other end 15 of input circuit 3 is connected to ground and through a cathode resistor 16 to the cathode 17 of said tetrode. The screen grid 18 is connected through the usual screen resistor 19 to the positive end of a source of potential 20 whose negative end is grounded (not shown) in the conventional manner. The anode 21 of tetrode 14 is connected in series with the primary 22 of a transformer 23 and the usual anode resistor 24 to the source of potential 20. The primary 22 is tuned by means of a condenser 25 to the intermediate or beat frequency and the output of the mixer is obtained from the secondary 26 of transformer 23. Conventional bypass condensers 27 and 28 are provided.

The oscillator 5 illustrated in Fig. 1 is a Hartley oscillator having a tank circuit 29 consisting of a tuning condenser 30, ganged to condenser 7, and a pair of coils 31 and 32 connected in series with padder condensers 33 and 34. Switch arm 35 forming part of multiple switch 11 connects either of said coils and its padder condenser across condenser 30, coil 31 being connected for the lower frequency band and coil 32 for the higher frequency band. One side 36 of condenser 30 is coupled through grid condenser 37 to the control grid 38 of a pentode 39, while the other side of condenser 30 is connected to ground. By-pass condenser 40 also couples the screen grid 41 of pentode 39 to ground at radio frequency. The suppressor grid 42 is connected in the conventional way inside the pentode to the cathode 43, which latter is in turn connected through switch arm 44 of multiple switch 11 to an end of the taps 45 or 46 on coils 31 and 32 respectively. The usual grid resistor 47 is connected between control grid 38 and cathode 43. The anode 48 is connected in series with a choke coil 49 having a tap 50, switch arm 51 of multiple switch 11, and a conventional anode resistor 52 to the source of positive potential 20. Likewise screen-grid 41 is connected through a screen resistor 53 to said source 20.

From an understanding of the conventional Hartley oscillator, it will be apparent that the tank circuit 29 of oscillator 5 will oscillate at a frequency controlled by the tuning of condenser 30 and depending on which of coils 31 and 32 is connected thereto, and that alternating current potentials of such frequency will appear across choke coil 49. These potentials are injected or fed into the mixer 4 by being applied across cathode resistor 16 thereof. For this purpose, one end 54 of choke coil 49 is coupled through condenser 55 to one side 56 of cathode resistor 16, while the other end 57 of choke coil 49 or the intermediate tap 50 is connected through switch arm 51 and coupled through condenser 58 to the other end 59 of cathode resistor 16. It will thus be seen that the oscillating potentials across choke coil 49 are applied across cathode resistor 16 and thereby fed into the mixer 4 and mixed with potentials derived from source 1.

Choke coil 49 forms part of a tuned circuit 6. The circuit may be traced as follows: beginning at end 57 or tap 50 of choke coil 49 through switch arm 51, condenser 58, resistor 16, con-

denser 55 back to the other end 54 of choke coil 49. In addition there are various shunt capacitances in the circuit to the ground side thereof to which end 59 of cathode resistor 16 is connected. These capacitances include stray capacitances of the circuit elements to ground and interelectrode tube capacitances to ground such as, for example, the capacity of anode 48 of pentode 39 to cathode 43 thereof which latter is in turn connected through part of coils 31 or 32 to ground. The value of choke coil 49 and the positioning of tap 50 thereof is such that this tuned circuit 6 is tuned to the lower end of whichever band of frequencies the tank circuit of the oscillator covers or more specifically to the lower end of the band of frequencies of the oscillator output. As will be explained herein-after, this causes the amplitude of the voltages applied across resistor 16 at the lower end of each band to be greater than at the upper end of each band. Because of the resistor in tuned circuit 6, the circuit is of relatively low Q and the value of this Q can be determined by changing the value of the resistor to provide the desired characteristic of variation of amplitude with change of frequency over a given band.

Referring now to Fig. 2 and particularly curves A, in which the horizontal axis represents frequency and the vertical axis represents the required input voltage applied to the input circuit of the mixer to produce a given output, and in which curve A₁ represents the lower frequency band and curve A₂ represents the higher frequency band, it will be seen that at the lower frequencies of each band, the required input voltage is greater than at the higher end of each band. This is primarily due to the fact that the L/C ratio is less at the lower end of each band, that is, the C of the tuning condenser 7 is greater at the lower end of each band than at the upper while the L is fixed. Moreover it will be seen in comparing curve A₁ representing the lower frequency band and curve A₂ representing the higher frequency band that this discrepancy between the lower end of each band and the higher end of each band is accentuated in the case of the higher band. This same low frequency discrimination may occur in stages prior to the mixer circuit too and thus increase the resultant total low frequency discrimination.

Not only is this discrimination against the lower frequencies apparent in the mixer circuit and prior stages but it is also apparent in the conventional oscillator circuit as represented by curves B in which the conventional oscillator output voltage is plotted against frequency. Curves B₁ and B₂ roughly indicate how the output of the conventional oscillator is less at the lower end of each band than at the upper end thereof.

To counter-balance this discrimination against the lower frequencies in each band, the output circuit of the oscillator is tuned so that it has its maximum output at the lower end of each band. This output voltage is proportional to the impedance of the tuned circuit and curves C of Fig. 2 indicate the effect of tuning said circuit to the lower end of one of said bands of frequencies. By tuning tuned circuit 6 to the lower end of the upper band of the oscillator output frequencies, the impedance of said circuit will vary as indicated in curve C₁ from a maximum 60 adjacent the lower end of the band to a minimum 61 at the upper end of the band. This impedance curve can be adjusted by changing the resistance of the tuned circuit 6 to produce a steeper impedance

curve such as, for example, curve C₂, the steepness of this curve depending upon the Q of the circuit. When the impedance of the output circuit of the oscillator is as illustrated in curve C₁, the resultant voltages injected into the mixer from the oscillator will be substantially as illustrated in curve B₃ of curves B. Since the output of the mixer circuit depends on both the voltages received from the source and the injected oscillator voltages, the resultant output of the mixer will tend to be substantially level over the entire band as illustrated by curve A₂ of curves A. This same correction will hold true for the lower band when the multiple switch 11 is operated to connect in the various coils of the low frequency band and the added inductance between tap 50 and end 57 of choke coil 49 so that the tuned circuit 6 is tuned to the lower end of the lower band.

While I have described by invention in connection with a specific oscillator and mixer, it will be apparent that other forms of oscillators and mixers may be substituted in place thereof as well as that the details of the described circuits may be varied without departing from the teachings of my invention. Accordingly, while I have described above the principles of my invention in connection with specific apparatus, it is to be clearly understood that this description is made only by way of example and not as a limitation on the scope of my invention.

I claim:

1. A source of alternating current energy, an oscillator including a tank circuit, a mixer adapted to mix energy from said source and said oscillator, said mixer having an input circuit coupled to said source, said input circuit and said tank circuit each being adapted to be tuned over a band of frequencies with the tank circuit tracking said input circuit, and a tuned circuit coupling the oscillator and mixer, said tuned circuit being fixedly tuned to a frequency at the lower end of the tank circuit band of frequencies.

2. The combination according to claim 1 wherein said mixer includes an electron discharge device having a cathode, and a grid coupled to one end of said input circuit, a cathode resistor having one end coupled to the cathode and the other end coupled to the other end of said input circuit, and

wherein said tuned circuit includes a choke coil connected in the output circuit of said oscillator across which coil alternating current potentials are developed, and means for applying said alternating current potentials across said cathode resistor.

3. A source of alternating current energy, an oscillator including a tank circuit, a mixer adapted to mix energy from said source and said oscillator, said mixer having an input circuit coupled to said source, said input circuit and said tank circuit each being adapted to be tuned over a plurality of bands of frequencies with the tank circuit tracking said input circuit, a tuned circuit coupling the oscillator and mixer, said input circuit and said tank circuit each including a tuning condenser and an inductance, and means for simultaneously switching in a different value of inductance in each of said input and tank circuits to select the band of frequencies over which each operates, and for fixedly tuning said tuned circuit to a frequency at the lower end of the selected band of frequencies of the tank circuit.

4. The combination according to claim 3 wherein said mixer includes an electron discharge device having a cathode, and a grid coupled to one end of said input circuit, a cathode resistor having one end coupled to the cathode and the other end coupled to the other end of said input circuit, and wherein said tuned circuit includes a choke coil connected in the output circuit of said oscillator across which coil alternating current potentials are developed, and means for applying said alternating current potentials across said cathode resistor, the aforesaid switching means being adapted to select the value of the inductance of said coil in accordance with the band of frequencies of said tank circuit.
